UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

SEWING-MACHINE.

1,129,592.

Specification of Letters Patent.

Patented Feb. 23, 1915.

Application filed September 10, 1907. Serial No. 392,211.

To all whom it may concern:

Be it known that I, LANSING ONDERDONK, a citizen of the United States, residing at New York, in the county of New York, State 5 of New York, have invented certain new and useful Improvements in Sewing-Machines, of which the following is a description, reference being had to the accompanying drawing, and to the letters and figures 0 of reference marked thereon.

My invention relates to sewing machines, and has for its object to provide a chain stitch sewing machine, wherein the stitch is formed and practically finished for each 5 reciprocation of the needle bar.

A further object of my invention is to provide a sewing machine of the above character, wherein the looper receives practically all its movements while the needle is on its 0 up stroke.

A still further object of my invention is to provide a stitch-forming mechanism, wherein the looper thread is transferred to a thread retainer, and the looper returned 5 to its extreme backward position, while the needle is on its up stroke.

These and other objects will in part be obvious, and in part be hereinafter more fully described.

0 In the drawings which by way of illustration, show one embodiment of my invention,—Figure 1 is a front plan view, showing a sewing machine embodying my improvement, the work support being removed to expose the looper-operating mechanism; Fig. 2 is a top plan view of a machine embodying my improvements, the feeding mechanism being broken away for the sake of clearness; Fig. 3 is a sectional detail 5 view, showing the feeding mechanism and the looper mechanism; Fig. 4 is a similar view with the needle in a different position; Fig. 5 is a detail showing in side elevation, the means for vibrating the thread retainer; 5 and Fig. 6 is a detail view, showing the rock arms for oscillating the looper. Fig. 7 is a side view of the parts shown in Fig. 6.

The bed plate 1 has rising therefrom an overhanging arm 2, carrying lugs at the forward end in which reciprocate a needle bar 3. The needle bar 3 carries a needle 4 at its lower end and receives its reciprocation from a lever 5. The lever 5 is connected to the needle bar by means of a link 6. The lever 5 receives its oscillation from an eccentric

strap 7, which coöperates with an eccentric 8 on the main shaft 9. Said main shaft is rotated by a belt wheel 10, or any other suitable means. A looper 11 is secured to an arm 12 by means of a screw 13. The looper-carrying arm 12 is pivoted at 14 to a stud 15, which is secured to a collar on the looper-supporting shaft 16. The looper-carrying arm 12 is provided with a ball stud 17, which is engaged by a link 18, which is pivoted at 19 to a stud 19 carried by a rock lever 20. The rock lever 20 is pivotally connected to a fulcrum stud 21, secured to the arm 2 of the machine. The rock lever 20 is provided with a second arm 22 (see 70 Fig. 2). The arm 22 has a collar formed integral therewith, to which the arm 20 is clamped by means of a set screw 23, so that the two arms 20 and 22 move together about the fulcrum stud 21. The arm 22 is connected to 75 a rock lever 24, by means of a link 25, which is pivoted to the outer end of the arm 22 at one end, and to the rock lever 24 at the point 26. The other arm 27 of the rock lever 24 is slotted, and provided with an adjustable stud 28. The stud 28 is connected to an eccentric strap 29 which coöperates with an eccentric 30 on the main shaft 9. A feed dog 31 is carried by the feed bar 32, which is pivoted to a rocking frame 33. The rocking frame 33 receives its movement from a crank disk 34 on the end of the shaft 9 in the usual manner. The looper support 16 has rigidly clamped thereto an arm 35, by means of a screw 36. The outer end of the 85 arm 35 is forked (see Figs. 3 and 4), and engages a cam 37 secured to the shaft 9. As the shaft 9 is rotated, the looper support 16 is oscillated to give the looper carried by said support its needle-avoiding movement. 90 Also as the shaft 9 rotates, the eccentric 39 rocks the lever 24, which in turn rocks the lever arms 22 and 20, and through the link 18 oscillates the looper back and forth in the direction of its length. 95

The thread retainer 38 is mounted in an arm 39, which is pivotally mounted upon a stud 40. The stud 40 is mounted in a split collar 41, carried on an arm 42, which is clamped by means of a screw 43 to a post 105 44, rising from the bed plate. The arm 39 at its rear end carries a ball stud 45, which is engaged by a link 46. The link 46 at its opposite end engages a ball stud 47, carried on the outer end of the arm 48. The arm 110

48 is provided with an offset member 49, and between the arm 48 and the member 49 rotates a cam 50 carried by the main shaft 9 of the machine. As the main shaft rotates, the arm 48 is vibrated up and down, thus imparting an up and down movement to the loop retainer 38. The axis of the pivot stud 40 of the arm 39, carrying the loop retainer 38 is inclined to the plane of the work support, so that the loop retainer as it vibrates up and down moves in a direction at an acute angle to the path of the needle.

The pivotal connection of the link 25 to the rock lever 24, is so disposed that as the lever 24 is rocked, said pivotal connection moves from the position at the left of a line connecting the fulcrum of the rock lever 24, and the pivotal connection of the link 25, to the arm 22, to a position slightly at the right of said line. The result of this position of the parts is that the looper on its return stroke moves rapidly out of the needle loop and the speed of the looper gradually decreases until the pivotal connection above referred to, reaches the line also referred to, at which time the movement of the looper ceases. The movement of this pivotal connection to the right of said line, as viewed in Fig. 1, gives little or no movement with the looper.

The operation of the machine is as follows: Starting with the needle at the lower end of its stroke, and the looper is at this time in its retracted position, just beginning its forward stroke, as the needle rises the usual needle loop is thrown out, which is entered very quickly by the looper, which passes on to the end of its stroke, reaching the same practically by the time the eye of the needle reaches the upper surface of the material. The looper is now moved laterally by the cam 37 and the thread retainer 38 moves up into the looper thread loop. The looper immediately begins its backward oscillation, and by the time the needle reaches the upper end of its stroke, said looper practically reaches the rear end of its stroke, leaving the looper thread loop upon the loop retainer 38. As soon as the looper point in its backward movement passes the needle path and the loop retainer, the needle loop taken by said looper on its forward stroke is shed or dropped, and the needle in completing its up stroke draws said needle loop up close to the work, finishing the stitch. It will thus be seen that I have provided a chain stitch sewing machine, including a threaded looper, which operates to form a chain stitch and to practically finish the stitch on the up stroke of the needle.

In my device, where the stitch is formed and practically finished on the up stroke of the needle, it will be noted that the needle in its final pull upon the needle thread to

set the stitch, is pulling the thread directly up through the needle puncture in the material, and, therefore, I am enabled to draw the stitch very tight. As a matter of fact, by my stitch-forming mechanism, I am enabled to draw the looper thread practically to the upper side of the material, if desired. 70

Having thus described my invention, what I claim as new and desire to secure by Letters Patent, is:—

1. A sewing machine including in combination, a needle, means for reciprocating said needle, a work support, a looper beneath the work support, means for moving said looper into the needle loop, laterally 80 while in the needle loop and for retracting the same out of the needle loop on the upward movement of the needle, a loop retainer, and means for moving said loop retainer into the looper thread loop prior to 85 the shedding of the needle loop from the looper.

2. A sewing machine including in combination, a work support, feeding mechanism, a needle means for reciprocating the 90 needle, a looper cooperating with said needle beneath the work support and moving in a plane substantially at right angles to the line of feed, means for moving the looper into the needle loop and out of the 95 needle loop on the upward movement of the needle, a loop retainer, and means for moving the loop retainer into the looper thread loop prior to the shedding of the needle loop from the 100 looper.

3. A sewing machine including in combination, a work support, a feeding mechanism, a needle, means for reciprocating the needle, a looper cooperating with said needle beneath the work support and moving in a plane substantially at right angles to the line of feed, means for moving said looper 105 into the needle loop and laterally while in the needle loop and then retracting the looper out of the needle loop on the upward movement of the needle, a loop retainer, and means for moving said loop retainer 110 into the looper thread loop prior to the shedding of the needle loop from the looper.

4. A sewing machine including in combination, a work support, a feeding mechanism, a needle, means for reciprocating the 120 needle, a looper cooperating with the needle beneath the work support and moving in a plane substantially at right angles to the line of feed, means for reciprocating said looper into the needle loop and for moving the looper laterally and then retracting the looper from the needle loop on the upward movement of the needle, a loop retainer moving in a plane inclined to the path of movement of the looper, and means for 125 130

moving said loop retainer into the looper thread loop prior to the shedding of the needle loop from the looper.

5. The combination with a needle, a looper, a thread retainer, means for moving said thread retainer into the looper thread loop and for moving said looper out of the needle loop on the upward stroke of the needle, and means for adjusting the 10 throw of the looper.

6. The combination with a needle, a looper, a thread retainer, coöperating with the needle beneath the material, a support therefor, a yoke pivoted to the bed plate of 15 the machine, a rotary shaft, a cam carried by said shaft for operating said yoke, and means for connecting said yoke to said retainer for oscillating the same on its support.

20 7. The combination with a needle, a looper, a main shaft, a rock arm connected to said main shaft, a second rock arm, and a link connecting said second rock arm to said first rock arm, and a link for connecting

25 the second rock arm to the looper, said rock arms being so disposed that the looper is moved into and out of the needle loop, while

the needle is on its upward stroke and said looper is given a dwell at the rear end of its stroke during substantially the entire 30 downward movement of the needle.

8. A sewing machine including in combination, a work support, a needle, means for reciprocating the needle, a looper, a looper arm on which said looper is mounted, means 35 for oscillating said arm in a direction substantially at right angles to the line of feed, means for swinging said arm laterally while the looper is at the forward end of its stroke, a loop retainer mounted for movement into the looper thread loop, an arm on which said loop retainer is mounted, means for pivotally supporting said arm for the loop retainer, whereby said arm swings in a plane inclined to the plane of movement of the looper-supporting arm, and means for oscillating said loop retainer arm. 40

In testimony whereof I affix my signature, in presence of two witnesses.
